UNITED STATES PATENT OFFICE

EDGAR H. BURROUGHS, OF SCARSDALE, NEW YORK, ASSIGNOR TO AMBURSEN CONSTRUCTION COMPANY, INC., OF NEW YORK, N. Y., A CORPORATION OF NEW YORK

DAM

Application filed May 23, 1930. Serial No. 454,873.

This invention relates to a novel and improved form of dam, the novel features of which will be best understood from the following description and the annexed drawing, 5 in which I have shown a selected embodiment of the invention, and in which:—

Fig. 1 is a view showing a dam constructed according to my invention, and taken on the line 1—1 of Fig. 2;

10 Fig. 2 is a view on the line 2—2 of Fig. 1;

Fig. 3 is a view on the line 3—3 of Fig. 2.

My invention is shown and has particular utility in connection with a dam of the type 15 in which an upstream inclined water bearing deck 3 is supported by a plurality of buttresses 4 beneath the deck and extending downstream therefrom. Under certain conditions, as where the dam extends across a valley and where the adjacent hillside has 20 faults, it has been known to stop the masonry structure before the surface of the hillside is reached and to form an extension of the dam in the shape of a fill, as of rock, disposed substantially in line with the masonry dam.

25 In such construction, it has been customary to permit the fill to extend around the end buttress and between the buttresses, it being assumed that this fill will counteract to a large extent the thrust of the body of the fill against 30 the masonry of the dam. The relative thrusts, however, are uncertain in quantity.

According to this invention, however, it is possible to avoid the above uncertainty, 35 and this is done by so designing the end buttress that it will be capable of taking the entire lateral thrust from the embankment and of preventing this thrust from being transmitted to the rest of the structure. This is done by projecting or extending this end 40 buttress into the embankment an amount sufficient to give it stability on all planes.

In Figs. 1, 2, and 3, I have shown a construction such as just mentioned above. The end buttress 6, as seen in Fig. 2, closely follows the outline of other buttresses and of the adjacent portion of the dam, but is designed for independent stability under the forces acting on it, as seen in Figs. 1 and 3. Then, behind the buttress 6 I place the embankment 2, preferably made of rock fill. 50

This fill may extend from this buttress up the hillside with its top 7 substantially level with the top 8 of the dam. The upstream face 9 and, if desired, the down-stream face 10 of this fill may be provided with facings of concrete to make the fill substantially watertight. The fill down-stream of the dam is supported on a slab 11 closing the down-stream face of the dam to prevent the fill 55 reaching beneath the dam.

60 By this arrangement the superstructure of the dam is relieved of all side thrust from the tendency of the material on the hill to slide toward the stream, this thrust being taken by the end buttress. Overturning of this 65 buttress may be resisted by the provision of steps 12 on its back, upon which will rest the material of the fill.

The distribution of lateral thrust on the end 70 buttress is exemplified in Fig. 3, by the trapezoid C. While the dimensions of this end buttress as herein described are appreciably greater than the ordinary adjacent buttresses at the point of maximum height illustrated by Fig. 1, they will be much smaller 75 in proportion for the lower heights of buttress such as shown by Fig. 3. This is because advantage may be taken of the weight of fill on both sides of the buttress to overcome the overturning moment caused by forces due to 80 lateral thrust as illustrated by Diagram C, while in constructions known to the prior art, the weight acting to the left of the end buttress will not aid it to resist overturning.

85 While I have shown the invention as embodied in a specific form, it is to be understood that various changes in details may be made without departing from the scope of the invention, and I therefore do not intend to limit myself except by the appended claim. 90

I claim:

In combination, a dam comprising an inclined upstream water bearing deck, a plurality of supports beneath said deck and extending downstream therefrom, a fill disposed at one end of the dam and forming a continuation of the dam for a substantial distance, an end support for said deck adjacent said fill and having an upstream and downstream profile substantially the same as that 100

of the adjacent portion of the dam, said end support retaining said fill and increasing in thickness from its top to its bottom and being projected into said fill a distance sufficient to insure stability thereof against thrust of the fill on all planes and against thrust from said deck, and means closing the down-stream face of the dam to prevent the fill from extending between supports.
